PACKING TRAY FOR CYLINDRICAL ARTICLES

Urban H. Despres, Clinton, Maine

Application July 16, 1953, Serial No. 25,968

Term of patent 14 years

(Cl. D58—13)

To all whom it may concern:

Be it known that I, Urban H. Despres, a citizen of the United States of America, residing at Clinton, county of Kennebec, State of Maine, have invented a new, original, and ornamental Design for a Packing Tray for Cylindrical Articles, of which the following is a specification, reference being had to the accompanying drawings, forming part thereof.

Fig. 1 is a top plan view of a packing tray for cylindrical articles, showing my new design.

Fig. 2 is a front elevational view thereof, partly in section and taken on the line 2—2 of Fig. 1, and

Fig. 3 is a cross-sectional view thereof taken on line 3—3 of Fig. 1.

I claim:

The ornamental design for a packing tray for cylindrical articles, as shown.
